UNITED STATES PATENT OFFICE.

ARTHUR E. THOMAS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WHIP ROLL FOR LOOMS.

Application filed February 11, 1924. Serial No. 691,931.

To all whom it may concern:

Be it known that I, ARTHUR E. THOMAS, a citizen of the United States, residing at Worcester, in the county of Worcester and

5 State of Massachusetts, have invented a new and useful Whip Roll for Looms, of which the following is a specification.

This invention relates to whip rolls for looms and more particularly to improvements in yielding whip rolls designed to prevent thick and thin places in the cloth.

In weaving certain types of fabric it is desirable to have a large supply of warp, necessitating large beams and beam heads.

15 Under these circumstances the whip roll is located very close to the beam head, and interferes with the latter when a new warp is to be placed in the loom. To facilitate handling the warp under such conditions I 20 have provided for raising the whip roll to a position where the beam will pass without interference.

Accordingly, the principal object of my invention is to provide means whereby a roll 25 of the type mentioned may be used with a very large warp beam, the roll being mounted so it may be swung away from the beam to make room for the removal of the latter.

30 With this general object and others which will appear as the description proceeds, my invention resides in the combination and arrangement of parts hereinafter described and set forth in the claims.

35 In the accompanying drawings, wherein one form of my invention is shown,

Fig. 1 is a side elevation of part of a loom having my invention applied thereto,

Fig. 2 is a rear elevation of the parts 40 shown in Fig. 1, and

Fig. 3 is a fragmentary top plan view showing parts of my invention in section.

Referring more particularly to the drawings it will be seen that the loom side 45 10 is provided with an open bearing or pocket 11 which receives the gudgeon 12 of the beam 13. The beam is provided with heads, one of which is indicated at 14, the head being provided with 50 a drum 15 by means of which friction may be applied to regulate the amount of yarn delivered to the harnesses. Upstanding from the loom side 10 is an arm 16 to which is bolted a stand 17, and as each side of the 55 loom is provided with one of these stands 17

and the parts associated therewith, the description given herein will be limited to the structure located on one side of the loom only.

The bearing 18 is formed integral with 60 the stand 17 and has a vertical bore which receives rod 19 by means of which the warp stop motion stand 20 may be supported. The upper part of the stand has a rearwardly extending horn 21 which is forked 65 as indicated at 22 to receive the forward end of arm 24 and pin 25 by means of which the arm is pivoted to the horn.

Arm 24 is provided with a slot 26 in which moves a block 27 through which passes one 70 of the journals 28 of the whip roll 29. The forward end of the arm is recessed as indicated at 30 to receive the end of compression spring 31 the rear end of which engages block 27 to push the same to the rear 75 end of the slot.

In order to limit downward motion of the arm and whip roll and also support the same the stand 17 is provided with a stop 80 32 which has two fingers 33 between which the lower edge 34 of the arm 24 is designed to rest.

As indicated in the drawings, the beam head is of such proportions that when it is to be taken out of the loom the upper 85 part thereof would engage the whip roll 29 unless the latter were mounted so as to move upwardly, as indicated in dotted lines in Fig. 1. The outer portion of the open bearing 11, indicated at 35, necessarily projects 90 upwardly and the gudgeon 12 must be raised sufficiently to clear said projection. Heretofore it has been common practice to remove the stand 17 from the loom when a new warp is to be replaced but this procedure involves 95 labor and time and also introduces the opportunity of varying the horizontal plane of the warp, indicated at 40, inasmuch as the vertical position of the whip roll is likely to vary with each new setting.

It is to be understood that when the depleted beam is to be taken from the loom, it may be raised without giving special attention to the whip roll, as the latter will swing upwardly when engaged by the beam head, the warp, if still uncut, permitting this motion of the roll. However, there is nothing to prevent the roll from being swing over to the opposite side of the pin 25 if so desired.

It will be apparent from the foregoing that I have provided a very simple means by which the whip roll can be located very close to the warp beam and be moved away 5 from the latter when occasion requires. The stop 32 serves to arrest the downward pull on the whip roll due to gravity and the pressure of the warp.

It will further be observed that in all 10 angular positions of the arm the spring 31 is effective to hold the whip roll and bearing blocks therefor in the same relative position and that although the weight of the whip roll when the arm is moved to the dotted 15 line position indicated at Fig. 1 would act against spring 31 yet when the parts assume operative position as indicated in full lines the spring is relieved from the force of 20 gravity and is required to act against variation in warp only because of the fact that the slot and spring are substantially horizontal.

Having thus described my invention it will be apparent that changes and modifications 25 may be made therein by those skilled in the art without departing from the spirit and scope of the invention and I do not wish to be limited to the details herein disclosed, but what I claim is:

30 1. In a loom having a frame, a beam to supply warp, a whip roll around a portion of which the warp extends, said roll being movable yieldingly in the direction in which the warp travels and being held normally 35 closely adjacent to the beam by its own weight and the pressure of the warp and being movable freely from normal position in a direction transverse of the direction of travel of the warp and away from the 40 beam to permit removal of the beam.

2. In a loom having a frame, a beam to supply warp, a whip roll around a portion of which the warp extends, said roll being movable yieldingly in the direction in which 45 the warp travels and also movable transversely of the direction in which the warp travels, said roll being normally closely adjacent to the beam, and a fixed stop against which said roll is normally held and from 50 which it may move freely in a direction away from the beam and transversely of the direction of travel of the warp to permit removal of the beam.

3. In a loom, a removable warp beam, pivoted arms above said warp beam, a yielding whip roll mounted for rectilinear movement on said arms, and a fixed stop to limit downward movement of the arms and roll and holding said roll closely adjacent to the beam, said arms being freely movable upwardly to carry said roll away from said beam to permit removal of said beam. 55 60

4. In a loom having a frame, a warp beam mounted thereon and removable therefrom by an upward movement, arms pivoted to 65 the frame, a yielding whip roll mounted for sliding motion on the arms in a substantially horizontal line, a stop for said arms to limit downward motion of the whip roll toward the beam and normally locating said roll in 70 the lowest position thereof closely adjacent the beam, said arms being freely movable upwardly away from the stop to carry the roll away from said beam to permit removal of the latter. 75

5. In a loom having a frame, a warp beam mounted thereon and removable therefrom by an upward movement, arms pivoted to the frame, a whip roll yieldingly mounted for sliding motion on said arms in a substantially horizontal line, and a stop for the arms 80 limiting downward movement of the roll, the arms being held in lowest position against the stop by the weight of the roll and the pressure of the warp thereon, the 85 arms being movable away from the stop to carry the roll away from the beam when the pressure of the warp is relieved to permit removal of the beam.

6. In a loom having a frame, a warp beam 90 mounted on the frame and removable therefrom by an upward movement, a whip roll, pivoted means to mount the roll for yielding rectilinear movement, and a stop to limit motion of the roll toward the beam, said roll 95 being normally in lowest position during the operation of the loom and held in such position by gravity and the pressure of the warp, said means being movable upwardly to carry the roll away from the beam when the pressure of the warp is relieved and the beam is 100 to be taken from the frame of the loom.

In testimony whereof I have hereunto affixed my signature.

ARTHUR E. THOMAS.
